UNITED STATES PATENT OFFICE

DAVID FIRTH, OF FLINT, MICHIGAN, ASSIGNOR TO MARVEL CARBURETER CO., OF FLINT, MICHIGAN, A CORPORATION OF ILLINOIS

EXPLOSIVE MIXTURE HEATING CONTROL

Application filed November 15, 1929. Serial No. 407,337.

This invention relates to a heat control for the intake systems of internal combustion engines.

It is the principal object of this invention to provide an improved and simplified heat control adapted to compensate for varying conditions of operation and engine temperature. In a variable speed and load type of carburetting engine, the maximum power output is obtainable with a cool incoming mixture of fuel and air since the cooler the mixture, the greater the weight of a unit charge delivered to the engine cylinder. At normal operating speeds, the distribution of the cool and consequently wet mixture can be taken care of by proper manifolding design. A manifold suitable for distribution at wide open throttle is obviously too big for the small amount of mixture supplied under idling conditions, so that, with a wet mixture, deposition of a portion of the liquid fuel results, due to the slow rate of flow in the manifold under such circumstances. The best method of overcoming such idling troubles is to supply heat to the intake manifold or carburetor, as by means of an exhaust gas heated jacket. To stop at this point would result in overheating the mixture under wide open throttle conditions, since the quantity and temperature of the exhaust gases increase as more mixture is supplied to the engine, and this would result in a serious loss in the maximum power obtainable from a given cylinder size. To overcome this difficulty, it is convenient to provide an exhaust control valve for the jacket supply and to link this valve to the engine throttle to progressively cut down the exhaust gas flow through the jacket as the throttle is opened.

The present invention goes farther in providing a temperature control superimposed on the control of the exhaust gases by the movement of the throttle. When the engine is operating under normal temperature conditions, in other words is thoroughly warmed up, the amount of heat required for smooth performance at or slightly above idling speeds or under light loads is very much less than in the case when operating a cold or

overcooled engine under similar conditions of load, since the cold engine will have a much greater condensing or separating effect on the mixture supplied thereto. It is accordingly an object of this invention to provide an improved and simplified temperature responsive control for modifying the supply of heat to the intake system, which control is supplemental to the throttle control of the heating effect.

Other and further important objects of this invention will be apparent from the disclosures in the specification and the accompanying drawings.

This invention (in a preferred form) is illustrated in the drawings and hereinafter more fully described.

On the drawings:

Figure 1 is a general elevation of the manifolding system of an internal combustion engine which embodies one form of the features of this invention.

Figure 2 is an enlarged vertical section showing the exhaust passages which supply the heating jacket, this section being in a plane parallel to Figure 1.

Figure 3 is an enlarged section on the line III—III of Figure 1.

Figure 4 is an enlarged section on the line IV—IV of Figure 1.

Figure 5 is a modified form of the invention wherein the exhaust control valve is manually controlled.

Figure 6 is another modification wherein the by-pass valve is thermostatically controlled separately from radiator shutters.

As shown on the drawings:

An internal combustion engine is indicated by a portion of the cylinder block 10 thereof, together with valve ports 11, an exhaust manifold 12, and an intake manifold 13 with its riser 14 having a carburetor mounting flange 15. The foregoing structures have been chosen for illustrative purposes in connection with the present invention, which is not limited in application to the arrangement shown.

The exhaust manifold 12 terminates in a flange to which is attached an exhaust valve housing 16 beneath which the usual exhaust

pipe 17 is attached. This housing has a straight through passage 18 containing a butterfly valve 19 on a cross shaft 20 operated by a lever 21. A carburetor 22 is attached to the mounting flange 15 and is formed with a jacketed section 23 surrounding the location of the throttle valve 24. This throttle is mounted on a shaft 25 which carries a lever 26 connected to the exhaust valve lever 21 by a link 27 in such a manner that the two valves operate substantially in unison, the exhaust valve being fully closed when the throttle valve is in its idling position.

15 The exhaust valve housing 16 is formed with a side outlet 28 forming a by-pass valve chamber horizontally divided by a partition 29 into upper and lower passages 30 and 31. The partition is apertured to receive a by-pass valve 32 mounted on a cross shaft 33, this valve serving to complete the partition when in the position shown in Figure 2.

20 The right-hand lip 34 of the valve aperture is extended downwardly to maintain cooperation with the corresponding edge of the valve 32 during the first part of the clockwise opening movement of the valve in order that the exhaust gases will not simply bypass from passages 30 and 31 and the exhaust 25 gases entering the upper passage 30 will not be guided by the top face of the partially open valve and thus deflected into the lower passage to the right of the valve, as such a flow would oppose the return movement of gases 30 through the lower passage 31 and would reduce the temperature of the intake gases at too early a period.

35 The side outlet 28 of the exhaust valve housing 16 is connected by a tube 35 to a side 40 outlet 36 on the carburetor heating jacket and this tube forms the return passage between the jacket and the lower passage 31 in the housing 16. The supply passage for the jacket is formed as a smaller bent tube 45 37 within the tube 35 and connecting the upper passage 30 of the housing 16 to the space within the jacket 23 beneath a deflector 38 which causes an initial flow of the gases 50 downwardly around the throttle location and thence upwardly around the edge of the deflector to the side outlet 36 of the jacket and into the outer tube 35. The return flow of the exhaust gases thus serves to conserve the heat of the gases passing through the bent 55 tube 37.

60 It is necessary to have the by-pass valve 32 cut off passage 30 when the valve is vertical, yet it is not desirable to have the valve restrict this passage when only partially closed. To accomplish this result, a projecting bridge 39 is formed on the wall of the side outlet 28 in a position to cooperate with the edge of the valve when in its vertical position. A ported bridge 39a may be provided

to cooperate with the lower edge of the valve if desired.

65 The by-pass valve shaft 33 may be manually controlled if desired, but preferably it is automatically controlled as a function of the operating temperature as, by this arrangement, provision of the maximum heat supply is assured for a cold engine, thus reducing the difficulty of starting under such conditions. One means of accomplishing 70 this result is to utilize a thermostatic member 40 associated with the engine cooling radiator 41, as shown in Figures 1 and 6. This thermostatic member may also desirably operate the usual radiator shutters, as shown in 75 Figure 1, since both the shutters and the heat control are advantageously controlled simultaneously and to substantially the same extent under given temperature conditions. The thermostatic member 40 is advantageously 80 situated in the lower portion of the radiator in order to be responsive to the temperature of the water supplied to the engine block. The member 40 expands with a rise 85 in temperature and pushes against the end 42 of a lever pivoted at 43, the other end 44 of the lever having a rod 45 linking it to a lever 46 on the by-pass valve shaft 33, thus 90 rotating this shaft clockwise.

95 In the modification shown in Figure 5, the exhaust control valve 19 has its lever 21 operated by a Bowden wire control 47 instead of being linked to the throttle. Such a control may be conveniently extended to the dash or operator's position, and has special advantages in simplicity under circumstances 100 where a more uniform and continuous load is imposed on the engine.

The operation

105 A consideration of the linkage and valve positions as shown in Figures 1 and 4 will show that for idling with a nearly closed throttle the exhaust valve 19 completely closes the main or direct passage through the valve housing 16. Thus the exhaust gases from the manifold are forced to flow into the upper part 30 of the side outlet 28 and thence through the inner tube 37 onto the heating jacket around the intake manifold riser. From the jacket the exhaust gases flow back through the outer tube 35 into the lower part 31 of the side outlet and thence into the main exhaust pipe. The return flow 110 envelops the inner tube and hence conserves the heat in the gases therein, thus assuring a greater heat supply to the jacket and materially shortening the warming up period.

115 The exhaust valve 19 may be arranged as shown, in order to have a delayed action in opening. This is accomplished by causing the valve 19 to move past its dead center on its closing movement. Therefore, as the throttle is opened, the exhaust valve 19 is 120 not opened as quickly as the throttle during 125

the initial opening movement, but does open fully when the throttle is open full. The exhaust flow is also increased due to the increased charge supplied to the engine and thus increases the pressure of the exhaust gases, which increased pressure will cause a continued flow through the heating jacket in spite of the initial opening movements of the exhaust valve. This continued flow will, however, be decreased as the exhaust valve opens further due to a decrease of back pressure at the wider opening of this valve.

The by-pass valve 32, when in its horizontal position, offers no resistance to the flow of exhaust gases to and from the heating jacket while it closes the by-pass around the main exhaust valve. The by-pass valve will be in the position mentioned when the thermostatic element in the lower tank of the radiator is collapsed due to a cold radiator or an overcooled one due to operating conditions. The thermostatic element preferably also operates radiator shutters to correct the last mentioned condition. As the thermostatic element expands in response to an increase in temperature, the linkage connecting to the by-pass valve rotates the latter toward its vertical position. The initial opening of the by-pass valve first opens the by-pass around the exhaust valve without materially restricting the area of the connections to the heating jacket, so that the effect of a partial opening of the by-pass valve is chiefly to relieve the back pressure on the exhaust gases in the manifold by providing a direct relief passage which materially reduces the flow through the heating jacket.

As the by-pass valve approaches its vertical position, the edges of the valve approach the bridges in the valve chamber and thus increasingly restrict the flow of exhaust gases toward and away from the heating jacket. In the vertical position, the heating jacket is thus entirely cut off from the exhaust manifold even though the engine is idling with the main exhaust valve closed, the exhaust gas flow in this case being through the port in the partition between the two conduits.

It will thus be seen that I have invented an improved and simplified heat control for the intake systems of internal combustion engines wherein a control of heat supply by the throttle is supplemented by a control responsive to the temperature of the engine cooling system.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In combination, an intake system in-

cluding a throttle and a heating jacket, means for conducting a heating fluid through said jacket, control means for directing heating fluid into said conducting means, means interconnecting the throttle with said control means for inversely proportioning the flow of heating fluid to the degree of throttle opening, and thermostatically operated means in said fluid conducting means for controlling the amount of heating fluid flowing therepast.

2. In combination, an intake system including a throttle and a heating jacket, means for conducting a heating fluid through said jacket, control means for directing heating fluid into said conducting means, means interconnecting the throttle with said control means for inversely proportioning the flow of heating fluid to the degree of throttle opening, valved means in said fluid conducting means adapted in one position to by-pass the heating fluid around said control means, and thermostatically operated means for operating said valved means.

3. In combination, an intake system including a throttle and a heating jacket, means for conducting a heating fluid through said jacket, control means for directing heating fluid into said conducting means, means interconnecting the throttle with said control means for inversely proportioning the flow of heating fluid to the degree of throttle opening, valved means in said fluid conducting means adapted in one position to close said conducting means and to by-pass the heating fluid around said control means, and thermostatically operated means for operating said valved means.

4. In combination, an intake system including a throttle and a heating jacket, means for conducting a heating fluid through said jacket, control means for directing heating fluid into said conducting means, means interconnecting the throttle with said control means for inversely proportioning the flow of heating fluid to the degree of throttle opening, a by-pass valve in said conducting means for controlling the flow of heating fluid therethrough, and thermostatic means for operating said by-pass valve.

5. In combination with the intake and exhaust manifold of an internal combustion engine, a heating jacket associated with said intake manifold, a valve in said exhaust manifold, supply and return connections for said heating jacket, said connections opening into the exhaust manifold on opposite sides of the valve therein, a by-pass valve controlling a passage between said connections, and thermostatically operated means for controlling said by-pass valve.

6. In combination with the intake and exhaust manifolds of an internal combustion engine, a heating jacket associated with said intake manifold, a valve in said exhaust mani-

- fold, supply and return connections for said heating jacket, said connections opening into the exhaust manifold on opposite sides of the valve therein, valved means in said connections adapted in one position to by-pass the flow of fluid therebetween and thermostatic means for operating said valved means.
7. In combination with the intake and exhaust manifolds of an internal combustion engine, a heating jacket associated with said intake manifold, a valve in said exhaust manifold, supply and return connections for said heating jacket, said connections opening into the exhaust manifold on opposite sides of the valve therein, valved means in said connections adapted in one position to close said connections to by-pass the flow of fluid therebetween, and thermostatic means for operating said valved means.
- 10 8. In combination with the intake and exhaust manifolds of an internal combustion engine, a heating jacket associated with said intake manifold, a valve in said exhaust manifold, supply and return connections for said heating jacket, said connections opening into the exhaust manifold on opposite sides of the valve therein, a valve in said connections for controlling the flow of heating fluid therethrough, and thermostatic means for operating said valve.
- 15 9. In combination with the intake and exhaust manifolds of an internal combustion engine, a heating jacket associated with said intake manifold, a valve in said exhaust manifold, supply and return connections for said heating jacket, said connections opening into the exhaust manifold adjacent to and on opposite sides of the valve therein, and a by-pass valve controlling a passage between said connections.
- 20 10. In combination, an intake system including a throttle and a heating jacket, means for conducting a heating fluid through said jacket, control means for directing heating fluid into said conducting means, means interconnecting the throttle with said control means for inversely proportioning the flow of heating fluid to the degree of throttle opening, valved means in said fluid conducting means adapted in one position to by-pass the heating fluid around said control means, control means in said fluid conducting means for controlling the flow of heating fluid therethrough, and thermostatic means associated with the engine cooling system for operating said control means.
- 25 11. In combination with the intake and exhaust manifolds of an internal combustion engine, a heating jacket associated with said intake manifold, a valve in said exhaust manifold, supply and return connections for said heating jacket, said connections opening into the exhaust manifold on opposite sides of the valve therein, a by-pass valve controlling a passage between said connections, and thermostatic means associated with the engine cooling system for operating said control means.
- 30 12. In combination with the intake and exhaust manifolds of an internal combustion engine, a heating jacket associated with said intake manifold, a valve in said exhaust manifold, supply and return connections for said heating jacket, said connections opening into the exhaust manifold on opposite sides of the valve therein, valved means in said connections adapted in one position to by-pass the flow of fluid therebetween, and thermostatic means associated with the engine cooling system for operating said control means.
- 35 13. In combination, an intake system including a throttle and a heating jacket, means for conducting a heating fluid through said jacket, control means for directing heating fluid into said conducting means, means interconnecting the throttle with said control means for inversely proportioning the flow of heating fluid to the degree of throttle opening, valved means in said fluid conducting means adapted in one position to by-pass the heating fluid around said control means, control means in said fluid conducting means for controlling the flow of heating fluid therethrough, and thermostatic means associated with the engine cooling system for operating said control means.
